UNITED STATES PATENT OFFICE.

NORMAN V. FITTS, OF DENVER, COLORADO, ASSIGNOR TO THE COLORADO IRON WORKS COMPANY, OF DENVER, COLORADO.

WORM-GEAR-OPERATED SLAG-POT CONSTRUCTION.

SPECIFICATION forming part of Letters Patent No. 752,635, dated February 16, 1904.

Application filed May 19, 1902. Serial No. 108,095. (No model.)

To all whom it may concern:

Be it known that I, NORMAN V. FITTS, a citizen of the United States of America, residing at Denver, in the county of Arapahoe and State 5 of Colorado, have invented certain new and useful Improvements in Worm-Gear-Operated Slag-Pot Constructions; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 My invention relates to improvements in worm-gear-operated slag-pot constructions, and especially to means for manipulating the trunnioned slag pot or receptacle after dumping.

20 In this specification I will show and briefly describe a slag-pot truck of ordinary type, so far as general construction is concerned, and my improvements will be set forth in detail. With a construction of this character the pot 25 or receptacle for receiving the molten slag as it comes from the furnace is of considerable size, and a worm engaging a worm-wheel fast on a trunnion of the pot is employed for dumping or discharging its contents, the worm 30 being turned by a hand-crank. Heretofore the operation of returning the pot to its upright or normal position after dumping has been accomplished by a reverse movement of the worm, which is slow, tedious, and results 35 in considerable loss of time.

My improvement consists in providing 40 means for normally disengaging the worm from the worm-wheel, whereby after the slag pot or receptacle has been tipped and the slag discharged the pot will return automatically to the upright position, since it is made heavier or thicker at the bottom to give it a normal tendency to return after its contents have been discharged.

45 Having briefly outlined my improved construction, I will proceed to describe the same in detail, reference being made to the accompanying drawings, in which is illustrated an embodiment thereof.

In the drawings, Figure 1 is a central vertical section of the apparatus. Fig. 2 is a top view of the same. Fig. 3 is an end elevation illustrating a slag-pot truck equipped with my improvements and showing the slag-receptacle in the upright or normal position. Fig. 4 is a similar view showing the said receptacle tipped to the dumping or discharge position, the bowl being broken to make room for the view above. Fig. 5 shows the worm-manipulating lever in two positions and on a larger scale, the worm wheel and shaft and the rock-shaft being shown in section. Fig. 6 is a detail view illustrating the locking device for the worm-shaft, shown on a larger scale than in the other views.

The same reference characters indicate the same parts in all the views.

Let the numeral 5 designate the body of the truck-frame, and 6 the wheels upon which the frame is mounted. On two opposite ends 70 of the slag-receptacle 13 the truck is provided with cogged racks 5^a, forming tracks for segmental gears 14, made fast to the respective trunnions 12 of the said receptacle. Extending upwardly from the body of the frame on 75 one end are two separated arms 5^a, to the upper extremity of which are attached extension-arms 5^c, in which is journaled a rock-shaft 7. To the extremities of this shaft outside of its bearings are attached boxes 8, in 80 which the worm-shaft 9 is journaled. These boxes 8 are provided with projecting hubs 8^a, made fast to the rock-shaft, whereby as the last-named shaft is moved the worm-shaft 85 may be raised. The worm portion 9^a of this shaft engages the upper portion of the periphery of a worm-wheel 10, made fast to one of the trunnions of the slag-pot, this trunnion being sufficiently extended for the purpose, as shown at 12^a. Fast on the rock-shaft 7 is 90 a lever-arm 15, provided with a spring-held dog 16, arranged to engage a notched bar 17, projecting upwardly from the frame of the truck, its upper portion being provided with a loop 17^a, forming a guide for the lever-arm, 95 which passes therethrough. When the lever is in the position shown in full lines in Fig. 1 and by dotted lines in Fig. 5, the worm is

in engagement with the worm-wheel. The opposite extremities of the worm-shaft are fashioned to receive a detachable hand-crank 18.

From the foregoing description the use and operation of my improved construction will be readily understood. Assuming that the hand-lever and worm are in the position shown in dotted lines in Fig. 5, if the worm-shaft be turned the pot or slag-receptacle 13 will be turned on its trunnions and tilted from the position shown in Fig. 3 to the discharge or dumping position shown in Fig. 4. Simultaneously with the dumping operation the pot is carried outwardly on one side of the truck by virtue of the engagement of the segmental gears with the racks 5^a.

To prevent the slag-pot from dumping accidentally or until the proper time, a locking-arm 19 is employed. This arm is pivoted on the rock-shaft 7 and provided with a recess or notch adapted to engage a part of the worm-shaft, which is angular, preferably square in cross-section. This construction is illustrated on a larger scale in Fig. 6 than in the other views. When the user is ready to dump the slag receptacle or pot, the locking device is disengaged from the worm-shaft and raised to the position shown by dotted lines in Fig. 6. The slag-pot may then be dumped by turning the worm-shaft, as will be readily understood. As soon as the slag has been discharged the lever-arm 15 is moved downwardly to the position shown by full lines in Fig. 5, whereby the worm-shaft is raised sufficiently to disengage the worm from its worm-wheel 10, when the slag-pot will immediately assume the upright position automatically by virtue of the fact that its bottom is made sufficiently thicker or heavier than the upper portion of its walls to produce this result.

Attention is called to the fact that by virtue of the shape of the slag-pot, whereby it is small at the bottom and increases in size toward the top when it is filled with slag, the greater portion of the contents is at the top, making the receptacle top-heavy, and therefore easy to tip to the dumping position. By throwing out the worm when the pot is full of slag it can when desired be dumped rapidly as well as operated by the gears. This is permitted by reason of the fact that the pot is top-heavy when full, as aforesaid. However, as soon as the slag is dumped the reverse is true and the pot-bottom is relatively heavy by virtue of the greater thickness of its lower portion, as described.

Having thus described my invention, what I claim is—

1. In a slag-pot-truck construction, the combination with a truck-frame, the slag-pot, the worm-shaft and the worm-wheel engaged by said shaft, of a rock-shaft journaled on the truck-frame parallel with the worm-shaft, boxes fast on the rock-shaft in which boxes the worm-shaft is journaled, and means for

operating the rock-shaft to lift the worm from engagement with the worm-wheel, substantially as described.

2. The combination with a slag-pot-truck frame, the slag-pot, a worm-wheel fast on a trunnion of the pot, and a worm-shaft whose worm engages the worm-wheel, of movable boxes in which the worm-shaft is journaled, a lever-arm and a suitable connection between the lever-arm and the movable worm-shaft boxes whereby the worm-shaft may be raised from engagement with the worm-wheel, as the lever-arm is actuated, substantially as described.

3. The combination with the slag-pot-truck frame, the slag-pot, a worm-wheel fast on a trunnion of the pot, and a worm-shaft whose worm engages the worm-wheel, of a rock-shaft parallel with the worm-shaft, worm-shaft journal-boxes provided with hubs fast on the rock-shaft, and means for imparting to the rock-shaft a partial rotation whereby the worm is lifted sufficiently to disengage it from the worm-wheel, substantially as described.

4. The combination with a worm-gear-operated slag-pot, of a rock-shaft extending parallel with the worm-shaft, worm-shaft journal-boxes connected with the rock-shaft to raise the worm-shaft as the rock-shaft is actuated, substantially as described.

5. The combination with a worm-gear-operated slag-pot construction, of means for disengaging the worm from its worm-wheel consisting of a rock-shaft having boxes in which the worm-shaft is journaled, substantially as described.

6. The combination with a worm-gear-operated slag-pot construction, of means for locking the worm-shaft against accidental movement, and means for disengaging the worm-shaft from the worm-wheel comprising a rock-shaft having bearings in which the worm-shaft is journaled.

7. The combination with a worm-gear-operated slag-pot construction, of a rock-shaft extending parallel with the worm-shaft, worm-shaft bearings fast on the rock-shaft, and means for actuating the rock-shaft to raise the worm from the worm-wheel, substantially as described.

8. The combination with a worm-gear-operated slag-pot construction, of a rock-shaft extending parallel with the worm-shaft, journal-boxes connected with the rock-shaft substantially as described, a lever-arm fast on the rock-shaft, a notched guide-arm through which the lever-arm passes, and a spring-held locking-dog mounted on the lever-arm and arranged to engage the notches of the guide-arm.

9. In a worm-gear-operated slag-pot construction, the combination of a rock-shaft suitably journaled, a connection between the rock-shaft and the worm-shaft whereby as the rock-shaft is actuated the worm-shaft is disengaged

from the worm-wheel, a lever-arm for operating the rock-shaft, and a device movably mounted on the rock-shaft for locking the worm-shaft against accidental movement, substantially as described.

10. In a worm-gear-operated slag-pot construction, the combination with a rock-shaft lying parallel with the worm-shaft, worm-shaft journal-boxes having hubs connected with the journal-boxes as described, said hubs being fast on the rock-shaft, a lever-arm fast on the rock-shaft, a notched guide-arm through which the lever-arm passes, a spring-held locking-dog mounted on the lever-arm and arranged 15 to engage the notches of the guide-arm, and a locking-arm mounted on the rock-shaft and having a recess adapted to engage a portion of the worm-shaft, to lock the latter against accidental movement, the worm-shaft being 20 formed angular in cross-section for the purpose, substantially as described.

11. In a worm-gear-operated slag-pot construction, the combination of a rock-shaft suitably journaled, and a connection between the 25 rock-shaft and the worm-shaft whereby as the rock-shaft is actuated the worm-shaft is disengaged from the worm-wheel.

12. In a dumping-car, the combination of a receptacle of greatest area at its top and gradually diminishing in area to its bottom and 30 trunnions supporting said receptacle at a point

to permit the lower end of the receptacle to overbalance the upper portion when empty and be overbalanced thereby when full.

13. In a dumping-car, the combination with 35 a semi-oval bowl or receptacle, trunnions supporting the same in such manner that the receptacle will be top-heavy when full, and means for slowly tilting the receptacle or permit it to rapidly dump. 40

14. In a dumping-car, the combination with a receptacle, of trunnions supporting the same in such manner that the receptacle will be top-heavy when full, segments on said trunnions, rigid platforms supporting the segments, a 45 worm-wheel on a trunnion, and a worm to turn said worm-wheel and roll the segments on the platforms to tilt the receptacle.

15. In a dumping-car, the combination of a receptacle pivotally supported and top-heavy 50 when full, a worm-wheel connected with the receptacle, a worm to turn said worm-wheel, and means for throwing said worm out of engagement with the worm-wheel to permit the receptacle to fall to its dumping position. 55

In testimony whereof I affix my signature in presence of two witnesses.

NORMAN V. FITTS.
